To all whom it may concern:

Be it known that I, Allen B. Gellman, a citizen of the United States, residing at Glencoe, in the county of Cook and State of Illinois, have invented a new, original, and ornamental Design for a Pyrophoric Lighter, of which the following is a specification, reference being had to the accompanying drawings forming a part thereof, in which:

Figure 1 is a side elevational view of a pyrophoric lighter embodying my new design.

Figure 2 is a plan view thereof.

Figure 3 is a front elevational view of the lighter.

Figure 4 is a rear elevational view of the lighter.

Figure 5 is a bottom view thereof.

This application is a continuation-in-part of applica-

tion Serial No. D.28,132 filed December 18, 1953, now abandoned.

I claim:

The ornamental design for a pyrophoric lighter, substantially as shown.
